ATTORNEY

UNITED STATES PATENT OFFICE.

WILLIAM G. SLAUSON, OF PAINESVILLE, OHIO.

ADDRESS-PLATE.

1,196,816.

Specification of Letters Patent. Patented Sept. 5, 1916.

Application filed September 15, 1913. Serial No. 789,845.

To all whom it may concern:

Be it known that I, WILLIAM G. SLAUSON, a citizen of the United States, residing at Painesville, in the county of Lake and State of Ohio, have invented certain new and useful Improvements in Address-Plates, of which the following is a specification.

My invention relates to address plates for addressing machines and is particularly well adapted for use on such machines when the plates are to be handled by electro-magnets.

The objects of my invention are: 1st. To provide a plate with reinforced or thickened ends so that the plates may be stacked in a galley without having their type faces in contact with adjacent plates. 2nd. To provide a curved plate which may be used on a rotary cylinder to print an address of more than two lines. 3rd. To provide a plate having longitudinal corrugations to stiffen the plate. 4th. To provide a plate having distinctive characters thereon to indicate a change of post office or railroad routing. 5th. To provide a plate having a non-printing letter to indicate the initial of the addressee so that the plates themselves form a card index. 6th. To provide a plate having notches arranged to expose the aforesaid index letters so they may be easily read when the plates are stacked in a galley. 7th. To provide a plate having a soft metal type face which may be hardened after the address has been embossed thereon. 8th. To provide a plate which may be engaged and held by a magnet and which is adapted to be used in the type of addressing machine shown in a co-pending application for Letters Patent of the United States filed by Wm. G. Slauson *et al.*, Oct. 25-1911, bearing Serial No. 656621.

To these ends my invention comprises the design of address plate illustrated in the accompanying drawing forming a part of this specification and in which—

Figure 1 is a plan view of one species of address plate. Fig. 2 is a plan view of a second species of address plate. Fig. 3 is a plan view of a third species of address plate. Fig. 4 is a plan view of a fourth species of address plate. Fig. 5 is an enlarged cross section of the address plate. Fig. 6 is an enlarged side elevation of one end of the plate.

Referring to the drawing the plate 1 is formed of a metal such as zinc, brass, alu-

minum or steel soft enough to receive the embossed address 2.

The plate 1 is provided with longitudinal corrugations 3 to stiffen it lengthwise and with thickened ends 4 so that the type face of one plate will clear the adjacent plate when the plates are stacked. The ends 4 are formed as shown in Fig. 6 by bending the metal upon itself, there being five thicknesses of metal shown in the figure. Instead of bending the metal upon itself a thickening piece could be welded on, or the same result could be obtained in a variety of other ways.

The plates are broadly speaking of two species, the difference being that one species is provided with a central notch 5, and in the other species this notch is omitted. The purpose of the notch 5 is to clear an electrical contacting device, which when touched by a passing plate closes a circuit to operate an alarm or other device.

The normal plates are each provided with a notch 5 but the plates at the end of the post office list, or other plates as may be desired, are formed without the notch 5, as shown in Figs. 1 and 2, and the said contacting device touches the middle portion 6 of the plates.

All the plates are provided with an index letter as shown at A—B—C and D. The plates coming alphabetically before the lettered plates are each provided with a notch as shown at 7—8—9 and 10, the said notch being opposite the letter to be exposed. For instance the notches 7 would serve for the letters A—E—I—M—Q—U and Y—the notches 8 would serve for the letters B—F—J—N—R—V—Z—the notches 9 would expose the letters C—G—K—O—S—W—and the notches 10 would expose letters D—H—L—P—T and X.

For convenience in manufacture, each plate would usually be provided with two notches either 7 and 10 or 8 and 9. However, only one letter as A—B—C—D would be stamped on each plate. In the drawing two are shown in order to illustrate their relation to the notches.

When used in an addressing machine in which the plates were fed over a cylinder, they would preferably be curved as shown in cross section Fig. 5 but obviously all the other features of construction could be used on flat plates.

When it is desired to handle the plates

by a magnet, they would preferably be made of soft steel and if so made they may be hardened after embossing by dipping them in a hot bath of cyanide of potassium.

5. Having now described my improved address plate I claim as my invention—

1. A one piece address plate provided with longitudinal corrugations, thickened ends and a type address.

10 2. A one piece address plate provided with longitudinal corrugations, thickened ends formed by bending the material upon itself and a type address.

15 3. A one piece address plate provided with longitudinal corrugations and thickened ends formed by bending the metal flat on itself, said plate being curved to fit the surface of a cylinder parallel to its length and provided with an embossed address.

20 4. A one piece soft steel address plate provided with longitudinal corrugations, thickened ends, an address and a body portion which may be engaged by a magnet.

25 5. A one piece metal address plate provided with longitudinal corrugations, thickened ends, and a notch to clear an electrical contacting device.

6. A one piece metal address plate pro-

vided with longitudinal corrugations, an embossed address, and thickened ends; said ends being raised above the printing side of the plate more than the letters forming the address.

7. A one piece address plate provided with thickened ends, an embossed address in the body of the plate between the ends, corrugations along the lower edge of the plate between the ends, and similar corrugations some distance below the upper edge of the plate.

40 8. A series of address plates each comprising a one piece address plate provided with thickened ends, an embossed address in the body of the plate between the ends, corrugations along the lower edge of the plate between the ends, and similar corrugations some distance below the upper edge of the plate, and a notch in the upper edge of some of the plates above the upper corrugations.

45 In testimony whereof I hereunto affix my signature in the presence of two witnesses.

50 WILLIAM G. SLAUSON.
